UNITED STATES PATENT OFFICE

CHARLES P. SCHLEGEL, OF ROCHESTER, NEW YORK, ASSIGNOR TO THE SCHLEGEL MANUFACTURING COMPANY, OF ROCHESTER, NEW YORK, A CORPORATION OF NEW YORK

UPHOLSTERY MOLDING

Application filed October 24, 1928. Serial No. 314,749.

The present invention relates to upholstery moldings and more particularly to the type in which there is provided a portion through which the nails or fasteners are passed to hold the strip in place, combined with means for covering the heads of the nails or fasteners. An object of this invention is to provide a novel and effective means for holding the covering member over the strip or web through which the nails are passed.

To this and other ends, the invention consists of certain parts and combinations of parts, all of which will be hereinafter described: the novel features being pointed out in the appended claims.

In the drawing:

Fig. 1 is a plan view of a molding constructed in accordance with this invention;

Fig. 2 shows a plan view with the covering strip moved to expose the nail or fastener head;

Fig. 3 is a section on the line 3—3, Fig. 2;

Fig. 4 is a section on the line 4—4, Fig. 1; and

Fig. 5 is a detail view of the wire channel member.

In the illustrated embodiment of the invention, 1 indicates the strip or web through which the nails are passed. This strip or web is formed with elastic material, such for instance, as textile fabric and has the nails or fasteners 2 passed therethrough. At one side of this web is provided a covering member comprising, in this instance, a filler 3 of rubber or other laterally bendable material. This filler has the textile fabric wrapped about the same at 4 and 5, which provides a hinged connection at 6 between the covering portion and the elastic portion 1. A pile surface 7 may be provided on the greater part of the portion 4 of the fabric, leaving the free edge of the covering member free of said pile surface as shown.

For holding the free edge of the covering member so that the latter will be retained over the strip or web 1 through which the nails are passed, a holding means of novel construction is provided. This holding means while laterally flexible provides an overhanging portion which is held in fixed re-

lation above the web portion. This result is secured, in this instance, by providing a laterally flexible holding device of channel form. In the present embodiment, this laterally flexible channel is formed from a single piece of wire bent to provide a series of U shaped loops providing connecting portions 8 and arms 9, the arms of adjacent loops being connected by bends 10 and lying parallel with each other. The arms 9 of all the U shaped loops 55 are bent intermediate of their ends at 11. The connecting portions 8 with portions of the arms 9 underlie the inner face of the web 1 while the portions of the arm 9 beyond the bends 11 overhang the inner face of the web 60 65 70 75 80 85 90 95 100

1 so that a channel is provided at that side of the web opposite the side to which the cover member is hinged in order to receive the free edge of the covering member and project over said covering member to a point adjacent the edge of the pile surface 7. This channel member is preferably covered on its outer face by the portion 12 of the textile fabric and on its inner face by the portion 13 of the fabric, a pile surface 14 being provided on the portion 12 so that when the covering portion has its free edge lying in the channel member, the two pile surfaces 7 and 14 will lie side by side and form a finished face to the molding. The channel member may be secured to the fabric in any suitable manner that will hold the upper wall of the channel in substantially rigid relation to the web 1. As the web 1 is elastic it may be stretched to shift the hinge 6 laterally in order that the free edge of the cover member may be pressed into the channel, after which the textile material contracts and holds the free edge of the covering member in the channel against accidental displacement. By introducing a sharp instrument between the cover member and the upper edge of the channel the cover member may be shifted so as to withdraw a portion therefrom after which the entire cover member may be forced by hand out of the channel.

This construction provides an effective means of holding the covering member at its free edge while giving a covering strip of substantially uniform contour in cross-sec-

tion and of minimum width while at the same time not providing any crevices in which dust or dirt may collect.

What I claim as my invention and desire to secure by Letters Patent is:

1. An upholstery molding comprising an elastic web through which a fastening device is passed, a cover for the fastening devices hinged at one edge to said web, an overhanging portion along the other edge of the web, and holding means having a channel formation and having its two walls substantially rigid with reference to each other, one wall extending into the overhanging portion, the edge of the cover being received in the channel between the two walls thereof.

2. An upholstery molding comprising an elastic web through which nails are passed, a cover for the web hinged at one side to the web, an overhanging portion along the opposite side of the web, and a laterally flexible channel member having its side walls arranged substantially in rigid relation to each other, one of said side walls lying below the cover and terminating in spaced relation to the hinge of the cover and the other of said side walls projecting onto the outer face of the cover for supporting said overhanging portion in closed position of the parts.

3. An upholstery molding comprising a web formed of textile material through which fastenings are passed; a cover including a filler and textile material in one piece with one side of the web extending about the filler; and holding means for the cover including a channel member having one wall extending over the web and textile material in one piece with opposite sides of the web extending over the other wall of the channel member and on the inner face of said channel member wall.

4. An upholstery molding comprising a web formed of textile material through which fastenings are passed; a cover including a filler and textile material in one piece with one side of the web extending about the filler; and holding means for the cover including a channel member having one wall extending over the web and textile material in one piece with opposite sides of the web extending over the other wall of the channel member and on the inner face of said channel member wall, portions of the textile material covering the outer face of the filler and the outer channel wall having pile surfaces thereon.

5. An upholstery molding comprising an elastic web through which nails are passed, a cover hinged at one edge to the web and arranged to cover the web, and holding means of channel formation embodying a single piece of wire bent to provide U shaped loops, the ends of the arms of which are connected together, the arms of the loops being bent between their ends to provide a laterally flexible channel, one side of which projects be-

neath the cover and the other side of which overhangs the swinging edge of the cover.

6. An upholstering molding comprising a back piece through which fastening devices are passed, a cover piece hinged at one edge to an edge of the back piece, a portion extending along the other edge of the back piece and overhanging said back piece and said cover piece in the covering position of the latter, and means for retaining the overhanging portion in overhanging relation to the back piece embodying curved devices lying transversely of the overhanging portion and having one portion which lies beneath the cover member when the latter is in covering position and another portion extending into the overhanging portion.

7. An upholstering molding comprising a back piece through which fastening devices are passed, a cover piece hinged at one edge to an edge of the back piece, a portion extending along the other edge of the back piece and overhanging said back piece and engaging said cover piece in the covering position of the latter, and means for retaining the overhanging portion in overhanging relation to the back piece embodying a plurality of metallic reinforcing devices extending into and transversely of the overhanging portion and beneath the cover piece when the latter is in covering position.

8. An upholstering molding comprising a back piece through which fastening devices are passed, a cover piece hinged at one edge to an edge of the back piece, a portion extending along the other edge of the back piece and overhanging said back piece, and means for retaining the overhanging portion in overhanging relation to the back piece embodying a plurality of bent wires extending into and transversely of the overhanging portion over the cover piece in the covering position of the latter and also beneath the cover piece when the latter is in covering position.

9. An upholstering molding comprising a back piece through which fastening devices are passed, a cover piece hinged at one edge to an edge of the back piece, a portion extending along the other edge of the back piece and overhanging said back piece to hold said cover piece in closed position, and means for retaining the overhanging portion in overhanging relation to the back piece embodying a laterally bendable reinforcing channel extending into the overhanging portion and also beneath the cover member when the latter is in covering position.

10. An upholstering molding comprising a fabric strip having an intermediate portion adapted to receive fastening means, one side of said strip being folded on itself to form at said fold a longitudinal hinge for moving a cover-forming edge portion of the strip to and from position to cover said fastening means, the other side of said strip being fold-

ed inwardly over said intermediate portion, and means for reinforcing said other side, said reinforcing means comprising a substantially rigid channel-shaped member having
5 one leg thereof lying beneath said cover-forming edge in closed position and the other leg thereof enclosed by said other side and forming therewith an overhanging portion spaced from said intermediate portion and
10 arranged to overlie and hold the cover forming edge portion in closed position.
